UNITED STATES PATENT OFFICE.

LOUIS B. FULTON, OF PITTSBURG, PENNSYLVANIA, ASSIGNOR TO THE CHAPLIN - FULTON MANUFACTURING COMPANY, OF PITTSBURG, PENNSYLVANIA, A CORPORATION OF PENNSYLVANIA.

STEAM-REDUCING VALVE.

SPECIFICATION forming part of Letters Patent No. 738,608, dated September 8, 1903.

Application filed December 8, 1902. Serial No. 134,355. (No model.)

To all whom it may concern:

Be it known that I, LOUIS B. FULTON, of Pittsburgh, in the county of Allegheny and State of Pennsylvania, have invented certain new and useful Improvements in Steam-Reducing Valves; and I do hereby declare the following to be a full, clear, and exact description of the invention, such as will enable others skilled in the art to which it appertains to make and use the same.

The object of this invention is to insure the presence of a column of water of condensation between the diaphragm of the valve-uniting mechanism and the delivery side of a steam-controlling valve, so that a non-metallic diaphragm may be employed and the operation of the device rendered quick and positive.

A further object is to provide against the device being rendered inoperative in the event of the diaphragm being punctured or otherwise damaged.

The invention will be hereinafter fully set forth, and particularly pointed out in the claim.

In the accompanying drawings, Figure 1 is a vertical longitudinal sectional view. Figs. 2, 3, and 4 are enlarged cross-sectional views on lines 2 2, 3 3, and 4 4, respectively, Fig. 1.

Referring to the drawings, 1 designates a valve-casing having the steam-inlet opening 2 and the outlet-opening 3, the communication between these two openings being controlled by a valve 4, having upper and lower stems 5 and 6, the former extending upwardly into a plug 7. This plug is screwed into the casing and at its lower end has a perforated cylindrical extension 8, which entirely surrounds the valve. By this perforated extension the steam is made to act directly against the valve under uniform pressure at all points, thereby relieving the same from any binding action against one side.

9 designates the diaphragm, of non-metallic material, secured between the flanged portions of a two-part casing 10, the upper part of such casing being directly connected to the lower portion of the valve-casing on the outlet side thereof by an extended tubular portion 12, thus forming a direct communication

between the upper part of the diaphragm-chamber and the outlet side of the steam-valve casing and providing for the confinement of sufficient water of condensation to prevent the same being blown out by the steam and avoiding any likelihood of the latter contacting directly with the non-metallic diaphragm. The latter is preferably made of leather or rubber, with the result that the action of the device is rendered quick and certain. To the lower part of the casing 10 is secured a depending cylindrical case 13, wherein is a spring 14, which tends to hold a plate 15 tight against the under side of the diaphragm. This plate 15 fits snug within a counterbored recess 16 in the lower part of casing 10, moving therein like a piston, and is further guided in its movements by a depending tailpiece 17 extended down within the coils of the spring. The tension of the latter is regulated by an adjustable screw 18 in the bottom of the case, engaging a block 19 in the end of the spring.

20 designates a rod extended longitudinally through the tubular portion 12 and at its lower end has a plate-like portion 21, which rests directly upon the diaphragm immediately above the piston-like plate 15. At its upper reduced end this rod projects into the valve-casing 1 and has a central bore to accommodate the stem 6 of valve 4. The rod is guided in its up and down movements by perforated flanges 22 and is further held in direct line by a spring 23, acting against valve 4. By means of the plate 15 having a piston-like action within its chamber or recess 16 the operation of the device will not be impaired even should the diaphragm be punctured or otherwise damaged, as the plate on the lower end of rod 20 is always held in tight relation to the plate 15.

The tension against the underside of the diaphragm exerted by the spring 14 is always greater than the steam-pressure against the top of the steam-valve, and hence normally the tension of such spring 14 will tend to hold the steam-valve open; but in practice water of condensation within the diaphragm-chamber and the tubular portion 12 is acted upon by the steam-pressure on the outlet side of the

valve-casing—that is to say, when the desired pressure has been secured in the parts or machines to which steam is being supplied any excess acts upon the column of water and forces the diaphragm downwardly as against the tension of spring 14 and allows the steam-controlling valve to be instantly seated under the direct action of the steam. Just as soon, however, as the pressure on the outlet side 10 becomes less than that for which the valve-unseating spring 14 is set, such spring overcomes the pressure in the diaphragm-chamber and effects the immediate unseating of the steam-valve. Thus the operation is continued, the steam-valve being alternately seated and unseated, according as the pressure on the outlet side of its casing is greater or less than that for which its controlling-spring is set.

20 The advantages of my invention are apparent. By reason of the fact that the steam cannot come in actual contact with the diaphragm, but must act on a column of water of condensation resting on the latter, I am enabled to make such diaphragm of rubber or leather, the same being protected from injury by the presence of the water. As before pointed out, should any damage occur to the

diaphragm the device will continue to operate, under proper conditions, by reason of the fact 30 that the valve-controlling rod is supported directly by the piston-like plate 15.

I claim as my invention—

The combination with the casing having inlet and outlet openings with a communicating port between them, and an opening in line with such port, of a valve designed to be seated against such port, a plug fitted in said opening having a perforated cylindrical extension surrounding said valve, a non-metallic diaphragm, a chamber therefor, an extended tubular connection between such chamber and the outlet side of the valve-casing, a rod supported by said diaphragm and engaging said valve, a piston-like plate movable in said chamber against the under side of the diaphragm, a spring bearing against said plate, and means for controlling the tension of said spring, substantially as set forth.

In testimony whereof I have signed this 50 specification in the presence of two subscribing witnesses.

LOUIS B. FULTON.
